UNITED STATES PATENT OFFICE.

JOSEPH EUGÈNE BAPTISTE MAILLARD, OF COULOMBS, FRANCE.

POWDER PUFF.

Application filed January 2, 1920. Serial No. 349,117.

To all whom it may concern:

Be it known that I, JOSEPH EUGÈNE BAPTISTE MAILLARD, a citizen of the Republic of France, residing at Coulombs par Nogent le Roy, France, have invented certain new and useful Improvements in Powder Puffs, of which the following is a specification.

The present invention has for its object a device containing a pulverulent substance such, for instance, as rice powder or absorbent powder and serving to distribute this substance by degrees. This device is so arranged that the powder is enclosed between a support and a permeable surface which prevents it from freely escaping while it can be pressed between said two surfaces and thereby distributed until the said powder is completely used up.

Two forms of the invention are represented by way of example in the accompanying drawing.

Figure 1 is a vertical section of the puff,

Figure 2 is a vertical section of a puff provided with a cover forming another puff, the cover being removed.

In Figure 1 the body of the puff is composed of a bottom piece 1 and a ring 2 in which the bottom piece loosely fits. These parts are preferably formed of cardboard. Secured upon the ring 2 by any suitable means is a disk 6 of cardboard or other suitable material, which is spaced from the bottom piece 1, and between which and said bottom piece is the spring 11. An envelope or cover 5 of textile fabric of fine mesh extends across the bottom of the ring and upon the sides of the same and has the edges secured upon the disk 6. Between the cover 5 and the bottom piece 1 the powder 4 is held.

As the bottom piece 1 fits loosely in the ring 2 and is subjected to the action of the spring 11, it acts as a piston to press the powder against the cover 5. In order to prevent the powder from passing between the ring and bottom piece an impermeable strip of fabric 12 has one edge secured to the lower portion of the ring 2 and its other edge to the lower face of the bottom piece 1.

The puff is provided with a handle of ribbon, paper, leather, or other material to permit it to be conveniently held. As shown the handle 7 is secured to the center of the disk 6 and passes through an opening in a disk 8, which rests on the edges of the cover 5 or envelope 5.

While the powder puff is shown round,

yet it is to be understood that it can be square, oval or any other shape.

In Fig. 2 the body of the powder puff is composed of a flanged ring of cardboard 2^a, upon which is secured a top piece which, as shown, is composed of two cardboard disks 6^a and 6^c and a felt or swankin washer 6^b, glued one on the other. The disk 6^c is covered with a fabric 6^d and provided with a tuft 65 of ribbon 7^a serving as a handle for the powder puff. The washer 6^b extends beyond the edge of the cardboard disk 6^c in order to prevent the unpleasant contact of the latter with the face.

The box is covered with two pieces of fabric 12^a and 5^a between which is enclosed the powder 4 and which are glued to the ring 2^a.

The outer fabric 5^a of jersey cloth for instance, is of suitable mesh for allowing the powder to pass through little by little according to the use of the powder-puff, whilst the fabric 12^a is as impenetrable as possible. A cardboard disk 1^a rests upon the fabric 12^a and between it and the disk 6^c is the 80 spring 11^a. The spring 11^a exerts a continual pressure on the fabric 12^a through the intermediary of a disk 1^a, so that the powder is always pressed against the fabric 5 until it is completely exhausted.

When the powder-puff thus formed is not in use it is advisable to fit it into a cover or sheath 15, or cardboard, for instance, covered externally with a thick fabric such as velvet or felt 16. This cover prevents the powder scattering on the articles in contact with which the puff might be placed; moreover, it may itself serve as puff for equalizing the powder deposited on the face and removing any superfluity thereof.

It is needless to say that of course the details of construction of the different parts of the devices as above described can be varied without departing from the invention, according to the materials employed for forming them, and the method of securing the several parts together.

I claim:

1. In a powder puff containing powder and serving for the gradual supply of the same, the combination of a bottom piece used as a bearing surface, a circular ring formed thereon, a movable disk disposed within the said circular ring, a spring disposed between the bottom piece and the movable disk, a band of impermeable fabric secured within the circular ring and upon the said mov-

able disk, a band of permeable fabric closing the open side of the circular ring, compressed powder between the movable disk and the said permeable fabric, a top portion covering the bottom piece on the outer side, and a handle disposed upon the said top portion.

2. In a powder puff containing powder and serving for the gradual supply of the same, the combination of a bottom piece used as a bearing surface, a circular ring secured thereto, a movable disk disposed between the bottom piece and the said movable disk, a band of impermeable fabric secured within the circular ring and upon the said movable disk, a band of permeable fabric closing the

open side of the circular ring, compressed powder between the movable disk and the said permeable fabric, a top portion covering the bottom piece on the outer side and a handle disposed upon the said top portion, 20 with a sheath adapted to receive the powder puff and a thick fabric covering the said sheath on the exterior.

In testimony, that I claim the foregoing as my invention I have signed my name in 25 presence of a subscribing witness.

JOSEPH EUGÈNE BAPTISTE MAILLARD.

Witness:

MAURICE ROUX.
